FILTER

Filed Sept. 5, 1922

Inventor:
William A. Heinze
By S. L. Bragg Atty.

UNITED STATES PATENT OFFICE.

WILLIAM A. HEINZE, OF CHICAGO, ILLINOIS, ASSIGNOR OF ONE-HALF TO PAUL B. MCKAIN, OF CHICAGO, ILLINOIS.

FILTER.

Application filed September 5, 1922. Serial No. 586,265.

To all whom it may concern:

Be it known that I, WILLIAM A. HEINZE, citizen of the United States, residing at Chicago, in the county of Cook and State of Illinois, have invented a certain new and useful Improvement in Filters, of which the following is a full, clear, concise, and exact description.

My invention relates to filters and is of particular service when employed for clarifying gasoline, though the invention is not to be limited to any particular use to which it may be put.

My improved filter includes a cage formed with inlet and outlet passages and an observing opening through the wall thereof, a filtering screen within the cage in the path followed by the liquid being filtered, and a transparent sleeve within the cage and surrounding the screen.

In the preferred embodiment of the invention the inlet and outlet passages are at one end of the filter cage and there are a plurality of observing openings at the mid portion of this cage. The other end of the cage is formed with an opening into which a plug is preferably screwed and this plug is formed with a liquid receiving cavity in its inner face that receives water which is precipitated from the gasoline, there being an outlet passage in the plug through which the water may be discharged when the smaller plug that normally closes this outlet passage is removed.

There is desirably also a pipe in communication with the first aforesaid outlet passage that is provided at one end of the cage with the inlet passage, this pipe being preferably in threaded connection with the portion of the cage in which this passage is provided and projecting from this cage portion toward the plug receiving portion of the cage. The pipe has its end which is nearer the plug receiving opening of the cage preferably closed and formed with a screwdriver slot whereby it may be readily applied and removed.

A filter screen surrounds the pipe and is bound at its ends thereto, the pipe having an opening in its side between the bound ends of the screen whereby communication is established between the interiors of the screen and pipe. A filter thus constructed may readily be observed without taking it

apart and may readily be taken apart when it is to be cleaned.

The invention will be more fully explained by reference to the accompanying drawing in which Fig. 1 is a longitudinal sectional view of a filter as it is preferably constructed; Fig. 2 is a sectional view on line 2-2 of Fig. 1; Fig. 3 illustrates the filter of my invention with some of the parts in separated relation and a portion of the screen broken away; Fig. 4 is a perspective view of the pipe which is surrounded by the screen; and Fig. 5 is a longitudinal sectional view of a modification.

Like parts are indicated by similar characters of reference throughout the different figures.

Referring first more particularly to the structure shown in Figs. 1 to 4 inclusive, the filter illustrated includes a cage 1 formed at one end with an inlet passage 2 and an outlet passage 3. The head portion of the filter is formed with four observing openings 5, 6, 7 and 8 which are distributed equidistantly around the cage which is generally cylindrical. A pipe 9 is in communication with the outlet passage 3 and is desirably in threaded connection with the portion of the cage in which this passage is provided. This pipe projects from this cage portion toward the other end of the cage and is desirably closed at the end thereof adjacent this latter cage end. A filter screen 10 surrounds the pipe and is bound at its ends thereto as indicated at 11 and 12. The pipe has lateral openings 13 between the bound ends of the screen, these openings serving to establish communication between the interiors of the pipe and screen. A glass or other transparent sleeve 14, preferably of cylindrical form, is disposed within the cage and surrounds the screen, the condition of the filter being observable through the openings 5, 6, 7 and 8 and the cylinder 14 that mechanically closes them. A gasket 15 seals the place of engagement of the upper end of the cylinder 14 with the seat in the cage that receives this cylinder end. A ring 16 is screwed within the lower end of the cage and carries a gasket 17 that is pressed against the lower end of the cylinder when the ring is screwed home. By this arrangement the cylinder becomes an integral part of the filter structure and co-operates with the up-

per and lower ends of the cage in confining the gasoline or other liquid that is to be filtered and in directing the flow thereof. A closure plug 18 is screwed into the lower end 5 of the filter cage normally to close the same and to permit the lower end of the cage to be open in order that the pipe 9 may be screwed into position or removed for cleaning or replacement. To facilitate the assembly of the pipe with the cage the lower end of the pipe is formed with a screwdriver slot 19.

The gasoline, for example, finds entry 15 through the inlet passage 2, and thence through the screen 10 from which it flows through the openings 13 and the bore of the pipe 9 to the outlet 3. Solid impurities are caught upon the screen and water is precipitated into the liquid receiving cavity 20 20 formed in the top of the plug 18. An outlet passage 21 is formed in the plug 18 to be in communication with the cavity 20. A closure plug 22 is screwed into the outlet passage 21 and may be removed to discharge 25 the water without the necessity of removing the plug 18. When the impurities have collected sufficiently upon the screen the plug 18 is removed and the pipe 9 is removed together with the screen 10 thereon to enable 30 the screen to be cleaned.

The structure shown in Fig. 5 is generally similar to that shown in the remaining figures and similar parts are given similar characters of reference.

In the structure of Fig. 5, however, the flow of gasoline is preferably reversed, finding access to the interior of the filter through the inlet 2' and exit through the outlet 3'. The pipe 9' in the structure of 40 Fig. 5 terminates at the top of the screen. The screen is cup-shaped and has its lower end assembled between the gasket 23 and the ring 16 instead of being tied to the pipe.

45 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

50 1. A filter including a cage formed at one end with inlet and outlet passages, at its mid portion with an observing opening formed through the wall thereof, and at its other end with a plug receiving opening; a pipe in communication with the outlet passage and in threaded connection with the portion of the cage in which this passage is provided and projecting from this cage portion toward the plug receiving portion 55 of the cage, said pipe having its end that is nearer the plug receiving opening of the

cage closed and formed with a screwdriver slot; a filtering screen surrounding said pipe and bound at its ends thereto, the pipe having an opening in its side between the bound ends of the screen; a transparent sleeve 70 within the cage and surrounding the screen; gaskets interposed between the ends of the sleeve and the cage to establish sealed tight assemblage between the cage and sleeve; a closure plug screwed into the plug receiving opening of the cage, this plug being formed with a liquid receiving cavity in its inner face and with an outlet passage communicating with this cavity; and a closure in the outlet passage of the plug. 75

2. A filter including a cage formed at one end with inlet and outlet passages, at its mid portion with an observing opening formed through the wall thereof, and at its other end with a closure receiving opening; a pipe in communication with one of the aforesaid passages and in threaded connection with the portion of the cage in which this passage is provided and projecting from this cage portion toward the closure receiving portion of the cage, said pipe having its end that is nearer the closure receiving opening of the cage closed and formed with a screwdriver slot; a filtering screen surrounding said pipe and bound at its ends 80 thereto, the pipe having an opening in its side between the bound ends of the screen; a transparent sleeve within the cage and surrounding the screen; a ring screwed into the cage against the sleeve; a closure for the closure receiving opening of the cage, this closure being formed with a liquid receiving cavity in its inner face and with an outlet passage communicating with this cavity; and a closure in this outlet passage. 90

3. A filter including a cage formed at one end with inlet and outlet passages, at its mid portion with an observing opening formed through the wall thereof, and at its other end with a closure receiving opening; a pipe in communication with one of the aforesaid passages and in threaded connection with the portion of the cage in which this passage is provided and projecting from this cage portion toward the closure receiving portion of the cage, said pipe having its end that is nearer the closure receiving opening of the cage closed and formed with a screwdriver slot; a filtering screen surrounding said pipe and bound at its ends thereto, the pipe having an opening in its side between the bound ends of the screen; a transparent sleeve within the cage and surrounding the screen; a ring screwed into the cage against the sleeve; and a closure for the closure receiving opening of the cage. 100

4. A filter including a cage formed at one end with inlet and outlet passages, at its mid portion with an observing opening 105

formed through the wall thereof, and at its other end with a closure receiving opening; a pipe in communication with one of the aforesaid passages and in threaded connection with the portion of the cage in which this passage is provided and projecting from this cage portion toward the closure receiving portion of the cage, said pipe having its end that is nearer the closure receiving 10 opening of the cage closed and formed with a screwdriver slot; a filtering screen surrounding said pipe and bound at its ends thereto, the pipe having an opening in its side between the bound ends of the screen; 15 a transparent sleeve within the cage and surrounding the screen; and a closure for the closure receiving opening of the cage.

5. A filter including a cage formed at one end with inlet and outlet passages, at its 20 mid portion with an observing opening

formed through the wall thereof, and at its other end with a closure receiving opening; a pipe within the cage and in communication with one of the aforesaid passages and projecting from this cage portion to 25 toward the closure receiving portion of the cage, said pipe having its end that is nearer the closure receiving opening of the cage closed; a filtering screen surrounding said pipe and bound at its ends thereto, the pipe 30 having an opening in its side between the bound ends of the screen; a transparent sleeve within the cage and surrounding the screen; and a closure for the closure receiving opening of the cage.

In witness whereof, I hereunto subscribe my name this 31st day of August A. D., 1922.

WILLIAM A. HEINZE.
